UNITED STATES PATENT OFFICE

CHARLES M. BECKER, OF BROOKLYN, NEW YORK

DESIGN FOR A LAMP OR ANALOGOUS ARTICLE

Application filed March 14, 1931. Serial No. 39,090. Term of patent 3½ years.

To all whom it may concern:

Be it known that I, CHARLES M. BECKER, a citizen of the United States, and a resident of the borough of Brooklyn, Kings County, city and State of New York, have invented a new, original, and ornamental Design for a Lamp or Analogous Article, of which the following is a specification, reference being had to the accompanying drawings, forming a part hereof.

Referring to the annexed sheet of drawings:

Figure 1 is a front elevational view of the lamp.

Figure 2 is a bottom plan view of the lamp.

The appearance of the lamp when viewed from the rear is substantially the same as the front view of Figure 1, except as to the seated figures.

I claim:

The ornamental design for a lamp or analogous article as shown and described.

CHARLES M. BECKER.
